US00D871005S

(12) **United States Design Patent** (10) **Patent No.:** **US D871,005 S**
(45) **Date of Patent:** **** Dec. 24, 2019**

(54) **MOP**

(71) Applicant: **Scot Young Research Limited**, West Midlands (GB)

(72) Inventor: **Ronald Alexander (Scot) Young**, West Midlands (GB)

(73) Assignee: **Scot Young Research Limited**, West Midlands (GB)

(**) Term: **15 Years**

(21) Appl. No.: **29/613,539**

(22) Filed: **Aug. 10, 2017**

(30) **Foreign Application Priority Data**

Feb. 10, 2017 (EM) 003747641-0001

(51) **LOC (12) Cl.** **07-05**

(52) **U.S. Cl.**

USPC **D32/50**

(58) **Field of Classification Search**

USPC ... D32/50-53, 40, 45, 17-18, 21-22, 24-25, D32/38; D4/130-132, 134-135, 138, 199

CPC A47L 13/52; A47L 13/12; A47L 13/00; A47L 13/20; A47L 13/24; A47L 13/22; A46B 7/04; A46B 7/06; A46B 5/00; B43M 11/02

(57) **CLAIM**

The ornamental design for a mop, as shown and described.

DESCRIPTION

FIG. 1 is a perspective view of the mop showing my new design;

FIG. 2 is a front view of the mop;

FIG. 3 is a first side view of the mop;

FIG. 4 is a second side view of the mop showing the side opposite the first side;

FIG. 5 is a rear view of the mop;

FIG. 6 is a top view of the mop; and,

FIG. 7 is a bottom view of the mop.

In the figures, any broken lines depict environmental subject matter and form no part of the claimed design.

1 Claim, 7 Drawing Sheets
